UNITED STATES PATENT OFFICE.

CLAYTON W. RUSSELL, OF SPRINGFIELD, OHIO.

STEERING MECHANISM FOR MOTOR-VEHICLES.

SPECIFICATION forming part of Letters Patent No. 787,471, dated April 18, 1905.
Application filed February 9, 1903. Serial No. 142,527.*To all whom it may concern:*

Be it known that I, CLAYTON W. RUSSELL, a citizen of the United States, residing at Springfield, in the county of Clark and State 5 of Ohio, have invented certain new and useful Improvements in Steering Mechanism for Motor-Vehicles, of which the following is a specification, reference being had therein to the accompanying drawings.

10 This invention relates to steering mechanism for motor-vehicles, and more particularly to improvements in that type of steering mechanism employing a steering-wheel located at the upper end of a steering-shaft.

15 My invention has for its object to provide a simple and efficient construction whereby the steering-wheel may be pivoted to the shaft, so as to be capable of being readily moved into a position such that it will not interfere with the movements of the operator when not in use, and may also be readily locked in position in firm operative engagement with the steering-shaft when in use.

20 To these ends my invention consists in certain novel features, which I will now proceed to describe and will then particularly point out in the claim:

25 In the accompanying drawings, Figure 1 is a perspective view of a motor-vehicle having my improvements applied thereto. Fig. 2 is an enlarged detail view, one-half in vertical longitudinal section, of the upper portion of the steering mechanism. Fig. 3 is a plan section taken on the line $x-x$ of Fig. 2 and 30 looking in the direction of the arrows. Fig. 4 is a vertical sectional view taken on the line $y-y$ of Fig. 2 and looking in the direction of the arrows. Fig. 5 is a vertical sectional view illustrating a modified form of connection, and Fig. 6 is a plan view of the same.

35 In the said drawings, 1 indicates the body of the vehicle, and 2 the operator's seat.

30 3 indicates the steering-shaft column, extending upward and rearward in an inclined direction and terminating slightly above and immediately in front of the seat.

4 indicates the steering-shaft mounted in the steering-column, which latter is provided with suitable bearings for said shaft, the 40 upper bearing being shown at 5. The shaft

proper terminates at the upper end of the column; but said shaft has secured to its upper end a head 6, which forms one member of a hinge-coupling which unites the wheel 7 to the shaft. This head 6 constitutes the male 55 member of the hinge-coupling, the same being provided at its front end with an apertured lug 8 to receive the pivot 9 of the coupling, while its rear end has a recess 10 to receive the locking-bolt of the coupling. Lateral 60 flanges 11 at the base of the head 6 form shoulders or seats on which the female member may rest. The head is further provided with a shank or extension 12, which fits within and connects said head with the upper end of 65 the shaft 4. It will be observed that the head 6 is non-circular in cross-section at right angles to the axis of the shaft, being of the rectangular form in cross-section shown.

The female member of the hinge-coupling, 70 which is connected to the wheel 7, is indicated at 13 and consists of a yoke-shaped member within which the head 6 fits, the free ends of the arms of the yoke being fitted on the pivot 9 and the arms themselves embracing between 75 them the sides of the head, being adapted to rest on the shoulders or flanges 11. The cross-bar of the yoke carries a sleeve 14, in which is mounted a locking-bolt 15, provided with a spring 16, which causes it to tend to engage 80 the recess 10 in the head 6. To prevent the locking-bolt from turning, so that its bevel will always be in proper position, the sleeve 14 is longitudinally slotted at its outer end, as shown at 17, to receive a pin 18, projecting 85 from the shank 19 of the bolt. By grasping the head 20 of the bolt said bolt may be drawn out far enough to clear its end from the recess 10, whereupon the two members of the coupling are disconnected and the wheel can 90 be turned upon the pivot 9. In Figs. 1 to 4 the female member or yoke 13 is shown connected with the wheel 7 by means of a connecting-piece 21, having a shoulder 22 and threaded shank or stem 23, the latter extending 95 into the hub of the wheel and secured therein by a sleeve-nut 24, which clamps the said hub against the shoulder 22.

It will be seen that by reason of the construction which I have devised the steering- 100

wheel is hinged to the steering-shaft immediately above and in close proximity to the upper end of the column, so that the steering-shaft is efficiently supported at its extreme upper end.

It will of course be understood that when the operator wishes to take or leave his seat the two parts of the hinge-coupling may be disconnected by drawing outward the locking-bolt, whereupon the wheel may be turned upward and forward around the pivot 9, so as to give ready access to or egress from the seat. When turned back into position, the wheel will be automatically locked to the shaft in an obvious manner. The construction of the hinge-coupling is such that it makes a strong and efficient connection between the wheel and shaft and occupies but little space longitudinally of the shaft, thus bringing the wheel into immediate proximity with the upper end of the shaft and of the column.

It will be observed that since the head and yoke constituting the male and female members of the coupling are non-circular in form the torsional strain is taken by these parts and the pivot is relieved from them.

Obviously the details of construction may be modified without departing from the principle of my invention. The recess of the female member may be formed directly in the body of the wheel instead of in a separate piece, as in the construction hereinbefore described, and in Figs. 5 and 6 I have illustrated such a modification, in which 25 indicates a rectangular recess formed in the hub and arms or spokes of the wheel and having a pivot 26 on one side and a locking-bolt 27 on the other, by means of which the wheel is connected with the head 28. In this con-

struction it is practicable to locate the pivot at a considerably greater distance laterally from the shaft than in the construction first described without rendering the construction objectionable. In either case the location of the pivot laterally with respect to the shaft brings the wheel into a plane at a desirable distance from the seat when swung up out of the way.

Other changes will readily suggest themselves, and I therefore do not wish to be understood as limiting myself to the precise details of construction hereinbefore described, and shown in the accompanying drawings.

Having thus fully described my invention, what I claim as new, and desire to secure by Letters Patent, is—

In a steering mechanism for motor-vehicles, the combination, with a steering-column having a bearing at its upper end, of a steering-shaft mounted in said column and bearing and provided with a transversely-elongated head substantially rectangular in cross-section transversely to the shaft, said head having a detent-recess in one end thereof, and a steering-wheel provided with a part having a rectangular recess to receive the rectangular head of the shaft, said part being pivoted at one end to the head on one side of the shaft, and a beveled spring locking-bolt mounted in the other end of said part to engage the detent-recess, said pivot and bolt lying in the same transverse plane, substantially as described.

In testimony whereof I affix my signature in presence of two witnesses.

CLAYTON W. RUSSELL.
